UNITED STATES PATENT OFFICE.

ROSS P. WRIGHT, OF ERIE, PENNSYLVANIA, ASSIGNOR TO REED MANUFACTURING COMPANY, OF ERIE, PENNSYLVANIA, A CORPORATION OF PENNSYLVANIA.

COLLAR-IRONING MACHINE.

1,373,580.

Specification of Letters Patent.

Patented Apr. 5, 1921.

Application filed June 21, 1917. Serial No. 176,084.

To all whom it may concern:

Be it known that I, Ross P. Wright, a citizen of the United States, residing at Erie, in the county of Erie and State of Pennsylvania, have invented new and useful Improvements in Collar-Ironing Machines, of which the following is a specification.

This invention relates to collar ironing machines and consists in certain improvements in the construction thereof as will be hereinafter fully described and pointed out in the claims.

Machines of this type are used for ironing the edges of collars. Ordinarily collars are ironed flat, then moistened along the folding edge so as to make them limp, placed on a former and this folding edge re-ironed. This relieves the collar of any strain in the folding and irons down any rough edges there may be.

In machines of this type a former and iron have been provided, the ironing pressure being delivered by hand. This pressure has been supplied by weighting or providing pressure for the iron as shown in the Patent 1,257,238, granted to John A. Hughes, for collar shaping and ironing machines, Feb. 19, 1918. It is particularly desirable where the iron is weighted to have some means other than the direct lift of the operator for lifting the iron off the former at the end of the collar. It will be understood that nearly all collars have a tab projecting slightly upwardly at the end of the collar so that in order to get the iron on to the collar it must be lifted slightly above the former. At the same time this end of the collar must be ironed. In the Hughes device this is accomplished by a cam which lifts the iron so as to clear the end of the collar and the cam is moved out of position to permit the ironing of the end of the collar by a foot pedal device. In the present invention these different operations are accomplished automatically by a mere swinging movement of the iron and this forms the principal object of the invention. Other details will appear from the specification and claims.

The invention is illustrated in the accompanying drawings as follows:

Figure 1 shows a plan view of the machine.

Fig. 2 a section on the line 2—2 in Fig. 1.

Fig. 3 a detail of the iron pivot.

Fig. 4 a side elevation with parts broken away to better show construction.

Fig. 5 a detail of the iron support.

1 marks the former, 2 the frame on which the former is mounted, 3 the iron, 4 a projection on the iron, 5 a handle for operating the iron, 6 an arm on which the iron is mounted, and 7 ears extending upwardly from a bearing 8, the arm 6 extending between the ears and being pivotally connected thereto by means of the pins 9. The bearing 8 has an extension 10 terminating in a flange 12. Balls 13 are arranged on the extension and flange and form a ball bearing in connection with the side walls of an opening 2^a in the frame and a plate 11 arranged over the opening 2^a and secured to the frame by means of the screws 11^a. By this arrangement the iron can be swung up and down and thus guided into proper relation to the former and can also be rotated in the usual manner of irons of this type.

Gas is supplied through a pipe 14 passing through a mixer 15, the mixer discharging into the arm 6, the arm being hollow for this purpose. A burner 16 is placed over the end of the arm and in the iron 3. The iron has the outlet opening 17 and inlet opening 18 for the flame.

The iron is also provided with the usual groove 19. The iron is secured to the arm 6 by a clamp 3^a. A screw 20 forms a means of adjustment determining the radial position of the iron in order that the groove 19 may be properly positioned on the former.

A pressure device for the iron is formed as follows:—A pocket 21 is formed on the arm 6, the side opposite the iron. A spring 22 is arranged in this pocket and rests on a plate 23. A screw 24 with a squared end 25 is screwed through the plate 23 and rests on a plunger 26. The squared end projects slightly from the pocket so that the screw may be turned and this moving the plate 23 varies the tension of the spring. Ears 27 are arranged on the plunger 26 and engage the arm 6 so as to prevent the plunger from turning in the pocket. A wheel 28 is journaled on a pin 29 secured on the plunger 26. The wheel rides on a track 30 on the plate 11, thus reducing the friction incident to placing the pressure device away from the center on which the iron swings.

An iron support 31 is in the form of a

yoke and has its arms extending up each side of the iron 3, the arms being pivotally mounted on the iron by means of a pin 32. A pin 34 extends into an opening 35 in a cross piece 33 of the yoke, the pin being secured in the opening by a cotter pin 36. The pin 34 has a head 37 adapted to form one of the run-ways of a ball bearing and the wheel 38 arranged to form the other run-way of the ball bearing is mounted on a pin, the balls 40 being arranged in the run-ways and forming a ball bearing for the wheel 38. A cam 41 is in the path of the wheel 38 when the support 31 is in its outer position. The cam 41 is so shaped as to carry the iron off the former when moved anti-clockwise as clearly shown in Fig. 4 by pressure exerted on the handle in a lateral or circumferential direction. The cam is arranged at the initial position of the iron so that as it is swung to this position it is carried off the former. A collar being put in place and the iron advanced the iron is carried above the former a sufficient distance along the former to clear the tab or end of the collar. The slope of the cam is such as to permit the iron to run down into engagement with the former. The support 31 is held in its outer position initially by a latch 43 which operates on a pin 42 on the support 31. The latch 43 is pivoted on one of the pins 9. A spring 44 extends from a perforation 45 in the support 31 to a hook 46 on the latch, the effect of the spring being to pull the support 31 inwardly when the latch 43 is out of engagement with the pin 42. The effect of the spring on the hook 46 operating as a bell crank tends to hold the latch 43 in engagement with the pin 42. As the wheel 38 rolls down the cam 41 and the iron is advanced in a clockwise direction (Fig. 1) the latch 43 comes into contact with a trip 47. This trip is pivotally mounted on an arm 48 on the frame by means of a pivot pin 49. The trip is held against swinging when the latch engages it with the advance movement of the iron by means of a stop 50. It will be noted, however, that when the latch strikes the trip 47 on a return movement, the trip swings on the pivot 49 as shown in dotted lines in Fig. 2 and does not release the latch. As soon as the latch is tripped with the advancing movement of the arm and the engagement of the latch on the upper surface 51 of the trip, the support 31 springs inwardly carrying the wheel 38 far enough in so that it will clear the cam 41. The iron can then be swung back to complete the ironing of the initial end of the collar. This being completed, the iron is advanced along the collar completing the ironing action throughout the length of the collar. As the iron is advanced it is desirable to again move the support 31 outwardly and to have it locked in this outer position by the latch 43

so that as the iron is returned by anti-clockwise movement to the initial position the wheel 38 will engage the cam 41 and lift the iron. A pin 52 extends from the cross piece 33 of the yoke and the cam 53 arranged on the edge of the plate 11 is in the path of this pin so that as the iron is advanced in the ironing action of the collar this pin 52 engages the cam 53, moves the support 31 outwardly so that the latch 43 snaps into position back of the pin 42 and locks the support in this outer position. As the iron is returned the latch engages the trip 47 but as before stated the trip when engaged with a movement in this direction swings on the pivot 49 and does not affect a release of the latch. It will be seen, therefore, that notwithstanding the fact that the iron is subjected to pressure it is automatically lifted or separated from the former in its initial position and is permitted to reengage the former to iron the initial end of the collar and the ironing operation of the collar is completed all automatically by pressure exerted on the iron in a circumferential direction.

What is claimed as new is:—

1. In a collar ironing machine, the combination of the ironing members, a former and an iron; means for moving one of the members into and out of engagement with the other and for moving one of the members along the other; means for separating the members by moving one of the members in a direction along the edge of the former; and mechanism for automatically throwing said last-mentioned means out of operative position as the members are moved relatively to each other.

2. In a collar ironing machine, the combination of the ironing members, a former and an iron; means for moving one of the members into and out of engagement with the other and for moving one of the members along the other; means for separating the members by moving one of the members in a direction along the edge of the former; and mechanism for automatically throwing said last-mentioned means into operative position as the members are moved relatively to each other.

3. In a collar ironing machine, the combination of the ironing members, a former and an iron; means for moving one of the members into and out of engagement with the other and for moving one of the members along the other; means for separating the members by moving one of the members in a direction along the edge of the former; and mechanism for automatically throwing said last-mentioned means into and out of operative position as the members are moved relatively to each other.

4. In a collar ironing machine, the combination of the ironing members, a former and

an iron; means for moving one of the members into engagement with the other and for moving one of the members along the other; means for separating the members near the 5 end from which the movement of the moving member begins along the other; and mechanism for automatically throwing said last-mentioned means out of operative position as the moving member is advanced whereby 10 the end of a collar is passed with the members separated and may then be ironed by a return movement of the moving member.

5. In a collar ironing machine, the combination of the ironing members, a former and 15 an iron; means for moving one of the members into engagement with the other and for moving one of the members along the other; means for separating the members near the end from which the movement of the moving 20 member along the other begins; devices for automatically throwing said last-mentioned means out of operative position as the moving member is advanced whereby the end of a collar is passed with the members separated and may then be ironed by a return 25 movement of the moving member; and means for throwing the mechanism into operative position as the moving member is further advanced.

30 6. In a collar ironing machine, the combination of the ironing members, a former and an iron; means for moving one of the members into engagement with the other and for moving one of the members along the 35 other; means for separating the members near the end from which the movement of the moving member along the other begins; mechanism for automatically throwing said last-mentioned means out of operative position 40 as the moving member is advanced whereby the end of a collar is passed with the members separated and may then be ironed by a return movement of the moving member; and means automatically throwing 45 the mechanism into operative position as the moving member is further advanced.

7. In a collar ironing machine, the combination of the ironing members, a former and an iron; means for moving one of the members 50 into engagement with the other and for moving one of the members along the other; means for separating the members near the end from which the movement of the moving member along the other begins; mechanism 55 for throwing said last-mentioned means out of operative position as the moving member is advanced whereby the end of a collar is passed with the members separated and may then be ironed by a return movement of the 60 moving member; and means automatically throwing said mechanism into operative position, as the moving member is further advanced.

8. In a collar ironing machine, the combination of the ironing members, a former and

an iron; means for moving one of the members into engagement with the other and for moving one of the members along the other; means for separating the members near the end from which the movement of the moving 70 member along the other begins, said separating means comprising as elements a cam on one of the members and a support on the other member; and automatic devices acting upon a relative movement of the members 75 for moving the elements out of register.

9. In a collar ironing machine, the combination of the ironing members, a former and an iron; means for moving one of the members into engagement with the other and for 80 moving one of the members along the other; means for separating the members near the end from which the movement of the moving member along the other begins, said separating means comprising as elements a cam 85 on one of the members and a support on the other member; and automatic devices acting upon a relative movement of the members for moving the elements out of register and holding said elements out of register during 90 a return movement of the member and for throwing the separating device into operative position with a further advance of the moving member.

10. In a collar ironing machine, the combination of the ironing members, a former and an iron; means for moving one of the members into engagement with the other and for moving one of the members along the other; a cam; a movable support on the iron adapted to engage the cam when in operative position; a latch holding the support in operative position; and a trip acting on the latch as the iron is advanced to trip the latch.

11. In a collar ironing machine, the combination of the ironing members, a former and an iron; means for moving one of the members into engagement with the other and for moving one of the members along the other; a cam; a movable support on the iron 100 adapted to engage the cam when in operative position; a latch holding the support in operative position; a trip acting on the latch as the iron is advanced to trip the latch only; and means for moving the support to 110 operative position and into position to be locked by the latch as the iron is advanced.

12. In a collar ironing machine, the combination of the ironing members, a former and an iron; means for moving one of the members 120 into engagement with the other and for moving one of the members along the other; a cam; a movable support on the iron adapted to engage the cam in operative position to lift the iron from the former; a 125 latch for holding the support initially in operative position; a trip for disengaging the latch as the iron is advanced; and a second cam engaging the support as the iron is further advanced and moving the support 130

again to operative position and into position to be engaged by the latch.

13. In a collar ironing machine, the combination of the ironing members, a former and an iron; means for moving one of the members into and out of engagement with the other and for moving one of the members along the other; means for separating the members by moving pressure exerted in 10 a direction along the edge of the former; mechanism for automatically throwing said last-mentioned means out of operative position as the members are moved relatively to each other; and a pressure device yieldingly exerting ironing pressure on one of the members.

14. In a collar ironing machine, the combination of the ironing members, a former and an iron; means for moving one of the 20 members into and out of engagement with the other and for moving one of the members along the other; means for separating the members by moving pressure exerted upon one of the members in a direction along 25 the edge of the former; mechanism for automatically throwing said last-mentioned means into and out of operative position as the members are moved relatively to each other; and a pressure device yieldingly exerting ironing pressure on one of the members.

15. In a collar ironing machine, the combination of the ironing members, a former and an iron; means for moving one of the 35 members into engagement with the other and for moving one of the members along the other; means for separating the members near the end from which the movement of the moving member along the other begins; mechanism for automatically throwing said last-mentioned means out of operative position as the moving member is advanced whereby the end of a collar is passed with the parts separated and may then be 45 ironed by a return movement of the moving member; and a pressure device yieldingly exerting ironing pressure on one of the members.

16. In a collar ironing machine, the combination of the ironing members, a former and an iron; means for moving one of the members into engagement with the other and for moving one of the members along the other; means for separating the members near the 55 end from which the movement of the moving member along the other begins; mechanism for automatically throwing said last-mentioned means out of operative position as the moving member is advanced whereby

the end of a collar is passed with the parts 60 separated and may then be ironed by a return movement of the moving member; means for throwing the mechanism into operative position as the moving member is further advanced; and a pressure device 65 yieldingly exerting ironing pressure on one of the members.

17. In a collar ironing machine, the combination of the ironing members, a former and an iron; means for moving one of the 70 members into engagement with the other and for moving one of the members along the other; a pressure device exerting pressure upon one of the members and a track on which the pressure device acts.

18. In a collar ironing machine, the combination of the ironing members, a former and an iron; means for moving one of the members into engagement with the other and for moving one of the members along 80 the other; a pressure device exerting pressure on one of the members; a roller on the pressure device; and a track over which the roller operates.

19. In an ironing machine, the combination of the ironing members, a former and an iron; means for moving one of the members into engagement and the iron along the former; a telescopic pressure device carried by the iron; and a track on which the pressure device operates as the iron is swung.

20. In an ironing machine, the combination of a former; an iron adapted to move along the former; a pressure device carried by the iron comprising telescopic members; 95 a spring operating on the telescopic members to exert pressure on the iron; means on one of the members for preventing it turning with relation to the other of said telescopic members; a roller carried by the pressure 100 device; and a track on which the roller operates.

21. In an ironing machine, the combination of a former; an iron adapted to move along the former; a pivotal mounting for the iron; a spring socket mounted on the iron; a plunger arranged in the socket; a spring arranged in the socket and operating on the plunger; a wheel carried by the plunger; a track on which the wheel operates; 110 and means for preventing the plunger from turning in the socket.

In testimony whereof I have hereunto set my hand.

ROSS P. WRIGHT.

In the presence of—

ARCHIBALD B. TOGER.
